UNITED STATES PATENT OFFICE.

LOUIS RICHARD HOLLOWAY, OF VICTORIA, TEXAS, ASSIGNOR TO CABIRANGE MANUFACTURING COMPANY, OF BELLEVILLE, ILLINOIS, A CORPORATION OF ILLINOIS.

DESIGN FOR A STOVE OR RANGE.

47,644.

Specification for Design.

Patented July 27, 1915.

Application filed March 22, 1915. Serial No. 16,297. Term of patent 3½ years.

To all whom it may concern:

Be it known that I, LOUIS RICHARD HOLLOWAY, a citizen of the United States, residing at Victoria, in the State of Texas, have invented a new, original, and ornamental Design for a Stove or Range, and of which the following is a specification, reference being had to the accompanying drawing, forming part thereof.

Figure 1. is a front elevation. Fig. 2. is a top plan. Fig. 3. is an end elevation.

I claim:

The ornamental design for a stove or range, as shown.

LOUIS RICHARD HOLLOWAY.

Witnesses:

H. R. AMELING,
MILDRED STOCKER.
